Primary Examiner — Jae Liang*Assistant Examiner* — Ji Sun Yoon(74) *Attorney, Agent, or Firm* — Egbert, McDaniel & Swartz, PLLC(57) **CLAIM**

The ornamental design for a leg for a cooler, as shown and described.

DESCRIPTION

FIG. 1 is an upper perspective view of a leg for a cooler showing my new design.

FIG. 2 is a top plan view thereof;

FIG. 3 is a bottom plan view thereof;

FIG. 4 is a front elevation view thereof;

FIG. 5 is a rear elevation view thereof;

FIG. 6 is a side view thereof; and,

FIG. 7 is an opposite side view thereof.

The broken lines illustrate portions of the leg for a cooler that form no part of the claimed design.
